ICE-SKATING RINK

Reuben J. Yocom, Omaha, Nebr.

Application July 11, 1949, Serial No. 104,018

13 Claims. (Cl. 62—12)

1
This invention relates to improvements in ice-skating rinks or the like and is concerned more particularly with the provision of novel means for marking the skating surface of such rinks, such means being also adapted for illuminating such skating rinks and imparting attractive decorative effects thereto.

It has been the customary practice to provide the necessary marked areas for ice-skating rinks, such as hockey rinks, by painting lines or other desired configuration directly on the ice or on the floor which supports the ice. Such markings are difficult for the players as well as the spectators to see and become particularly obscured after skates have chipped and roughened the surface of the ice.

It is an object of the present invention to avoid the foregoing disadvantages and to provide a novel marking arrangement for ice-skating rinks which will be readily visible to the players and spectators alike and which will remain so regardless of the condition of the surface of the ice.

A further object of the invention is to provide a simple and novel means for illuminating ice-skating rinks and for providing decorative and attractive designs particularly useful for spectator ice-skating shows, such means being adapted for use alone or in cooperation with other means of illumination such as the under ice lighting arrangement which forms the subject matter of my prior Patent No. 2,457,619.

Other objects and advantages of the present invention will be apparent from the following detailed description taken in conjunction with the accompanying drawings wherein a preferred embodiment of the principles of the invention has been selected for exemplification.

In the drawings:

Fig. 1 is a plan view of an ice hockey rink embodying the improvements of the present invention and illustrated in fragment;

Fig. 2 is an enlarged transverse section and partly broken away taken along the line 2—2 of Fig. 1;

Fig. 3 is an enlarged transverse section taken along the line 3—3 of Fig. 1 and partly broken away; and

Fig. 4 illustrates an enlarged transverse section partly broken away a modification of the construction shown in Figs. 1—3.

Referring more particularly to the drawings wherein like numerals refer to like parts, 10 indicates in its entirety a one-half section of a conventional ice hockey rink, it being understood that the remaining section is a duplica-

tion of that shown. The rink 10 is provided with the usual end boards 12 and side boards 14, player boxes 16 and penalty box 18. The goal cage is indicated at 20. Such parts are included for illustrative purposes only and form no part of the present invention.

The various hockey rink markings, with which the present invention is immediately concerned, comprise the goal lines 22 and goal creases 24, 10 the parallel zone lines 26, the penalty shot lines 28, the center face-off mark 30 and special spots 31. The goal lines and crease, the penalty shot lines and the face-off marks are usually red in color and the remaining markings usually ultramarine blue. The lines ordinarily are from two to twelve inches in width.

It is the concept of the present invention to delineate the foregoing markings either in whole or in part by strips of material having light 20 conducting properties as, for example, methyl methacrylate resin, one popular form of which is presently manufactured and sold under the designation Lucite. Such a strip of material is indicated at 32 in Fig. 2 and, as shown, such 25 strip 32 may be supported on the rink floor 34 and buried beneath the ice layer 36. A source of light for each strip 32 may be provided in a recessed portion of the rink sidewall and end-wall such as indicated at 38. The lamps 38 may be disposed at either one or both ends of the strip 32 and are positioned in such a manner that light from such source is conducted throughout the length of the strips 32 so as to be visible from the surface of the ice. The intensity of the light may be varied at will from a soft glow visibly to indicate the marking to a bright light to illuminate the rink or the performers thereon. The color desired may be provided by appropriate selection of the color of the strip or at the light source or both.

As is apparent, certain of the markings above referred to are not intended to extend the full width of the rink and, to provide for such markings, the invention contemplates the expedient illustrated in Fig. 3 wherein a continuous strip 40 is provided similar to that indicated at 32 but provided with sheathing of metal or opaque coating 42 to blank out the portions thereof which are not intended to form a part of the rink markings but leaving exposed those portions through which the light may be visible to indicate the marked area.

It will be understood of course, that a strip section could well be provided of the exact length or configuration of such inner rink markings as

the penalty shot lines 28 and the light source could be disposed adjacent such strips directly under the ice. It is usually desirable, however, to recess the light sources beyond the periphery of the rink, as shown, so as to shield the ice from the emitted heat.

In the modified construction shown in Fig. 4, the ice-skating rink comprises a floor of glass or other light transmitting material 44 which supports refrigerant tubes 46 preferably also of light transmitting material and the usual ice layer 36. In such modified construction, the strips of light transmitting material 48 and the light sources 50 therefor may be disposed beneath the glass floor and supported on the main 15 flooring indicated at 52.

The invention contemplates that the novel illuminating strips herein illustrated and described may be used alone to provide any desired rink markings or may be used on conjunction 20 with the conventional paint or other opaque material. It is particularly intended that the novel illuminating strips herein disclosed and described may be used in conjunction with direct under ice illumination such as the neon or other gaseous tubes disclosed in my prior Patent No. 2,457,619. In a convenient adaptation, the luminous strips of the present invention which emit a minimum of heat may be employed in any desired patterns to provide rink illumination of long duration together with the gaseous tubes of the said patent to provide special illumination of relatively short duration for various acts of ice skating entertainment shows.

It will be understood that the present invention is not confined to the particular constructions and arrangements herein described and illustrated but is limited only by the scope of the following claims.

I claim:

1. An ice skating rink comprising, a skating surface, refrigerating means for said skating surface, a source of light adjacent the boundary of said surface and strips of light conducting material positioned beneath and extending transversely of said skating surface to convey light from said source to selected areas of said rink.

2. The rink of claim 1 wherein the strips are of synthetic resinous material.

3. The rink of claim 2 wherein the material of 50 the strips is a methyl methacrylate resin.

4. An ice hockey rink comprising, a floor, a layer of ice having a skating surface supported by said floor, refrigerating means for said ice layer, a source of light located laterally beyond the boundary of said skating surface, and strips of light conducting material positioned beneath said skating surface and exposed to said source to define marked areas for said rink.

5. An ice skating rink comprising, a skating surface, refrigerating means for said skating surface, a boundary for said surface, a source of light disposed beyond said boundary and a strip of light conducting material positioned beneath and extending transversely of said skating surface to convey light from said source to selected areas of said rink.

6. The rink of claim 5 wherein the strip of light conducting material extends substantially

the width of the rink and wherein portions of the strip are sheathed to prevent exposure of the light.

7. An ice skating rink comprising, a rink floor, a skating surface supported by said floor, a source of light adjacent the boundary of said skating surface and a strip of light conducting material supported by said floor beneath said skating surface and exposed to said source of light whereby to convey light to selected areas of said skating surface.

8. The combination of claim 7 wherein the rink is an ice hockey skating rink and the strip of light conducting material is partially sheathed along its length to expose light in selected areas only whereby to define the marked line portions of said rink.

9. The combination of claim 1 additionally including a floor of light transmitting material and wherein the skating surface is supported by said floor.

10. The combination of claim 1 additionally including a floor of light transmitting material supporting the skating surface and wherein the refrigerating means includes refrigerant conduits of light transmitting material.

11. The combination of claim 7 additionally including a marked area for the skating surface and wherein the strip of light conducting material is disposed adjacent said marked area whereby to convey light to said marked area.

12. The combination of claim 7 wherein the rink is an ice hockey rink and there are a plurality of light sources and strips of light conducting material to define marked areas for the rink, selected of said strips having portions thereof sheathed to prevent exposure of light.

13. The combination of claim 7 wherein the rink is an ice hockey rink and additionally including hockey rink markings for the skating surface, there being a plurality of light sources and strips of light conducting material, and the strips of light conducting material being disposed adjacent said markings whereby to convey light to said markings.
